(57) **CLAIM**

The ornamental design for a light unit as shown and described.

DESCRIPTION

FIG. 1 is a top perspective view of a light unit showing our new design and showing in broken lines a lighting device in which it may be included;

FIG. 2 is a top view thereof;

FIG. 3 is a bottom view thereof;

FIG. 4 is a left side view thereof;

FIG. 5 is a right side view thereof; and,

FIG. 6 is a front view thereof.

The dashed broken lines are provided to show portions of the lighting device that form no part of the claimed design.

In FIGS. 1-5, the break line marks the boundary of the claimed design. The break line itself does not form part of the claimed design.
